Asbel Welch

United States Patent Office.

ASHBEL WELCH, OF LAMBERTVILLE, NEW JERSEY.

Letters Patent No. 93,146, dated July 27, 1869.

IMPROVED RAILWAY-CAR TRUCK.

The Schedule referred to in these Letters Patent and making part of the same.

To all whom it may concern:

Be it known that I, ASHBEL WELCH, of the town of Lambertville, in the county of Hunterdon, and State of New Jersey, have invented a new and useful Mode of Supporting the Bodies of Railroad-Cars on their Trucks; and I do hereby declare that the following is a full, clear, and exact description of the construction and operation of the same, reference being had to the annexed drawing, and to the letters of reference marked thereon, which make a part of this specification, in which—

Figure 1 is a side view of a six-wheeled truck on my improved plan;

Figure 2 is a top view of the same;

Figure 3 is a cross-section of the same, through the central axle;

Figure 4, a side view of my improvement as applied to a four-wheeled truck;

Figures 5 and 6 are diagrams of different kinds of hangers; and

Figure 7, a diagram of one kind of bolster.

The details of the car unconnected with my improvement are not represented, because my improvement is more plainly shown without such details.

My invention consists in extending the swinging frame beyond the outside of the truck-frame, for the purpose of supporting thereon springs of any kind, placed outside of the truck-frame, as well as inside, to carry the weight of the car-body; in using for that purpose, and so placed, elliptic springs, extending parallel with the axis of the car; and in supporting the car-body on said springs by means of a bolster, extending beyond the outside of the truck-frame, setting at right angles on all of said springs, and carrying both the centre and side vibration-plates; and also in another arrangement, in supporting the car-body on said springs, so supported and placed, by means of a shorter bolster, carrying the centre and side vibration-plates, and resting, at each end, on cross-bars laid across each pair of springs.

The main objects of my invention are—

First, by the said extension of the swinging frame, and by placing springs on the ends thereof, under the outer part of the car, to get such breadth of bearing for the body as to prevent excessive rolling, and the lurching so common and, so unpleasant and injurious in the top-heavy cars now deemed necessary for comfort, and coming more and more into use; and, by such greater breadth of bearing, to be able to use much more delicate springs, without rolling or unsteadiness, and, if thought best, to increase the width of the body, and thus to gain the great advantages of the broad gauge on a narrow-gauge railroad.

Second, by bringing all the springs that support the

car-body on a six-wheeled truck into one line parallel with and over the centre axle, to avoid the greater number and greater extent of the vibrations caused in such trucks by the ordinary disposition of the springs in two lines between the axles, at a distance from the centre of motion of the truck-frame, and thus to avoid one of the principal disadvantages of the six-wheeled truck.

Third, by the arrangement proposed, to use elliptic steel springs on the swinging frame in six-wheeled trucks, instead of spiral, gum, or some inferior springs, without spreading the wheels, and so increasing the weight and the difficulty of passing around sharp curves, and even then being limited in length of spring, which I avoid, thus avoiding the other principal objection to six-wheeled trucks, so that their great and obvious advantages may be gained without their disadvantages.

In the accompanying drawings—

a^2 represents the centre, and a^1 a^3 , the other axles of a six-wheeled truck.

b^1 b^2 , the sills, and C^1 C^2 , cross-pieces of the truck-frame.

d^1 d^2 are axles of a four-wheeled truck.

E^1 E^2 , the sills of the car-body, and

F^1 F^2 F^3 F^4 , the centre-frame, on which the car-body rests; and

F^5 , the centre bearing-timber, under the bolster.

G , the centre vibration-plate.

h^1 h^2 h^3 , the side vibration-plates, at which I put small gum springs, to prevent shocks.

The truck-frame may be supported by elliptic springs, resting on the journal-boxes, by gum, spiral, or other springs, on equalizing-bars, or in any other way.

The swinging frame is composed of the swinging bars k^1 k^2 , or the single swinging bar L , and the spring-bearers m^1 m^2 m^3 m^4 , or in a four-wheeled truck, n .

The swinging bars, of wood, iron, or steel, suspended by the hangers o^1 o^2 o^3 o^4 , or o^5 and o^6 , or o^7 , extend out between the wheels, beyond the outside of the truck-frame. The middle of these may be very light, and they may, if thought best, be jointed at j^1 j^2 , to allow equalization of pressure on the two springs of each pair, when the car is unequally loaded.

On, and at right angles to the swinging bars, are set and secured the spring-bearers m^1 , m^2 , m^3 , m^4 , or n , of iron or steel—one of each pair inside the other, outside the truck-frame—generally, but not necessarily, equidistant from the hanger. The outer one should be as far out as possible, under the outside of the body, so that the spring placed upon it may have as much leverage as possible, to keep the body from rolling too much.

In four-wheeled trucks, these bearers, as shown at n , are short rigid bars. In six-wheeled trucks, they

may either be elastic half springs, or rigid bars, arched, if necessary, spanning over the line of the central axle, from one swinging bar to the other.

The hangers may be either inside, as at $o^1 o^2 o^3 o^4$, or outside of the truck-sill; or they may rest on the top of the sill, as o^7 , and form a loose collar around it. They may be either in one link, or be jointed near the middle of their length, as shown at $j^1 j^2$. I prefer to make them as long as possible, with joints, and stops at the joints, to limit the vibration of the upper link, so that there shall ordinarily be all the easy swing of the long hangers, and yet, by the shortness of the radius of the arc described by the lower end of the lower link, when the motion of the upper link is stopped, and the consequent rapid rise of the weight by further vibration, that any excessive lateral movement of the car-body shall be stopped quickly, but without shock.

The elliptic springs P^1, P^2, P^3, P^4 , or P^5 , placed longitudinally, are set on and clamped to the spring-bearers, the middle of each spring being, in all cases, at the middle of the length of the truck. The springs, by this arrangement, can be increased to any length that may be desirable.

The centre and side vibration-plates, which carry the body, are set on the extended bolster q , of wood, iron, or steel, which rests, at right angles, upon, and is clamped to all the four springs. In another arrangement, shown in fig. 7, the vibration-plates are set on a shorter bolster, r , each end of which rests on the

middle of a cross-bar, s , which is supported by, and clamped to the two springs on that side of the car.

I do not claim the extended swinging frame, the longitudinal elliptic springs, nor the bolsters, when used for any other purpose, or combined in any other way, substantially different from that herein set forth, nor any other substantially different mode of supporting the car-body outside of the truck-frame.

What I do claim as my invention, and desire to secure by Letters Patent, is—

1. The extension of the swinging frame beyond the outside of the truck-frame, when used for the purpose specified.

2. The extended bolster, used for the purpose specified.

3. The combination of the swinging frame so extended, the elliptic springs placed longitudinally outside of the truck-frame, as well as inside, and the extended bolster, arranged and combined substantially in the manner and for the purposes specified.

4. The combination of the swinging frame and springs, before described, with the shorter bolster and cross-bars, arranged and combined substantially in the manner and for the purposes specified.

ASHBEL WELCH.
